UNITED STATES PATENT OFFICE

154,137

DESIGN FOR A PASSENGER LOADING RAMP

Proctor W. Nichols, Colorado Springs, Colo.

Application December 19, 1947, Serial No. 143,239

Term of patent 14 years

(Cl. D14—3)

To all whom it may concern:

Be it known that I, Proctor W. Nichols, a citizen of the United States, residing in Colorado Springs, in the county of El Paso and State of Colorado, have invented a new, original, and ornamental Design for a Passenger Loading Ramp, of which the following is a specification, reference being had to the accompanying drawing, forming part thereof.

In the drawing:

Figure 1 is a perspective view of a passenger loading ramp, showing one side of my new design; and

Figure 2 is a perspective view showing the opposite side thereof.

I claim:

The ornamental design for a passenger loading ramp, as shown.

PROCTOR W. NICHOLS.
